MOTOR FUELS OF HIGH OCTANE VALUE

Warren Nevin Norton Knight, Sunbury-on-Thames, England, assignor to The British Petroleum Company Limited, Finsbury Circus, London, England, a British joint-stock corporation

No Drawing. Application December 27, 1956
Serial No. 630,764

Claims priority, application Great Britain
January 11, 1956

1 Claim. (Cl. 208—62)

This invention relates to the production of high octane 15 motor gasolines of adequate volatility.

Catalytic cracking and hydroforming are among the processes which contribute to the production of high octane gasolines. In the catalytic cracking process, a petroleum feedstock boiling above the gasoline boiling range is cracked in the presence of a catalyst to produce hydrocarbons boiling in the gasoline boiling range, while in the hydroforming process, petroleum naphthas that have a low octane number are contacted at elevated temperature in the presence of hydrogen with a catalyst capable of converting naphthenes into aromatics to give a product of greatly increased octane number. A hydroforming process that has been widely adopted uses a platinum-containing catalyst and such a process will hereinafter be referred to as platinum reforming.

In the specification of the copending application Ser. No. 622,259, filed November 15, 1956, now Patent No. 2,897,027, there is described the preparation of high octane motor gasoline of adequate volatility by blending between 40% and 60% by volume of a high octane, low volatility component consisting of the higher boiling fraction of a platinum reformat, constituting 40% to 60% by weight of the platinum reformat, and between 60% and 40% by volume of a high octane, high volatility component consisting of the lower boiling fraction of catalytically cracked gasoline having an end boiling point between 80° and 120° C. As a result, there remains a light, that is, lower boiling, fraction of the platinum reformat having a relatively low octane number and high volatility and constituting 40% to 60% by weight of the platinum reformat, and a heavy, that is, higher boiling, fraction of the catalytically cracked gasoline, having a relatively high octane number and low volatility and an initial boiling point between 80° and 120° C., and unless otherwise treated these materials can only be disposed of as low grade gasoline.

In accordance with the present invention, these materials are together subjected to thermal reforming to produce a motor gasoline of at least 100 octane number Research with 1.5 ml. TEL/IG.

The conditions under which the thermal reforming treatment should be carried out will depend upon the properties of the blend and those required in the final product, but in general the following conditions will be found to be suitable:

Temperature ..... 1000° to 1200° F.
Pressure ..... 200 to 1200 p.s.i.g.
Conversion ..... Up to 25% wt. C₃
and lighter.

The invention will now be described with reference to the following example.

Example

In the specification of the aforesaid copending application Ser. No. 622,259, now Patent No. 2,897,027, a high octane gasoline is described comprising 55% by vol-

2

ume of a light catalytically cracked gasoline having a boiling range of C₅ to 100° C., and 45% by volume of a 45% weight platinum reformat residue. The associated light platinum reformat and heavy catalytically cracked gasoline when blended together give a gasoline of 82 Research octane and a volatility of 50.5% evaporated at 100° C. Inspection data on these materials are given in the following table.

	10	Light platinum reformat	Heavy Cat. Cracker Gasoline	Blend 63% vol. light platinum reformat, 37% vol. heavy cat. cracker gasoline

This blend was thermally reformed at 750 p.s.i.g and 35 1050° F. to a conversion of 19% weight C₃ and lighter, and gave a gasoline (67% weight yield) of 97.5 octane number Research clear (100 Research octane number +1.5 ml. TEL/IG) and a volatility of 42% evaporated at 100° C.

40 I claim:

A process for the production of a motor gasoline of at least 100 octane number (Research) with 1.5 ml. TEL/IG, which comprises separating a platinum reformat into lower boiling fraction constituting between 45 40% and 60% by weight of the reformat and having a relatively low octane number and high volatility, and a higher boiling remainder constituting between 60% and 40% by weight of the reformat and having a high octane number and low volatility; separating a catalytically cracked gasoline into a lower boiling fraction having an end boiling point between 80° and 120° C., and a higher boiling remainder having a relatively high octane number and low volatility and an initial boiling point between 50 80° and 120° C.; blending together said lower boiling fraction of said platinum reformat and said higher boiling remainder of said catalytically cracked gasoline; thermally reforming the resultant blend at a temperature of 55 1000° F. to 1200° F. and a pressure of 200 to 1200 p.s.i.g to effect a conversion of up to 25% wt. of the 60 blend to C₃ and lighter; and, recovering, as a product, a motor gasoline of at least 100 octane number (Research) with 1.5 ml. TEL/IG.
